(57) **ABSTRACT**

A security device for preventing or inhibiting unauthorized separation of a first part (e.g., a cable filter device) from a second part (e.g., a cable signal source) includes a connector having first and second connector parts which are freely rotatable with respect to each other, the first connector part including a male threaded end for removable connection to the first part and the second connector part including a female connector end for removable connection to the second part. A cylindrical sheath extends in covering relation to the first and second connector parts and is freely rotatable with respect thereto. In the attached condition, the first and second connector parts are accessible for attachment and removal only with a specially configured tool.

SECURITY DEVICE

BACKGROUND OF THE INVENTION

The present invention generally relates to tamper-proof security devices, and more particularly relates to a security device which may be attached to any two parts to inhibit unauthorized detachment of the parts from each other. In the embodiment shown and described herein, the security device is configured to attach to a cable connector or cable filter device to prevent or substantially inhibit the unauthorized removal thereof from the cable signal source.

Cable filter devices (also referred to as "cable traps") are well known and are used by cable companies to block the transmission of unauthorized communication transmission signals (e.g., television channels) from a cable signal source to the customer's television set. The cable filter device includes the channel blocking electronics, typically located on a printed circuit board, positioned within a cylindrical housing having F-connectors at either end to detachably connect to mating F-connectors at the signal source and the cable leading to the television set. F-connectors are threaded connectors which are standard sized coax cable connecting elements within at least the U.S. market. As such, cable filter devices are easily attached and removed from the mating F-connectors at the source and cable leading to the television set. Unauthorized, illegal removal of the cable filter device has unfortunately been a common problem resulting in loss of revenue by the cable provider.

SUMMARY OF THE INVENTION

The present invention addresses the problem of unauthorized removal of cable connectors or cable filter devices by providing a security device which prevents or at least substantially inhibits the unauthorized removal of the cable connector or cable filter device from the cable signal source and cable leading to the television set.

The security device generally comprises first and second connectors, the first connector part having opposite threaded male and female ends and the second connector part having a smooth shank and a threaded female head portion. The smooth shank is inserted into the central bore of the first connector part and the parts are secured together via a radially extending flange at the terminal end of the smooth shank which engages with the shank of the first connector part. As such, the first and second connector parts are secured together while allowing one to rotate freely with respect to the other without axial translation of one part relative to the other. A cylindrical sheath is positioned in covering relation to the first and second connector parts and may freely rotate thereon, again, with no axial translation of the sheath relative to the first and second connector parts. Specially configured tools are provided to allow authorized personnel to alternately attach and remove the security device from the parts to which it is connected (e.g., the connector and cable filter device). Without the specially configured tools, any attempt to remove the cable filter device is futile due to the freely rotating sheath covering the security connector parts. It is noted that installation of the security device to a first part (e.g. filter) can be done in the field with one of the specially configured tools but may alternately be done at the manufacturer whereby the security device is shipped already attached to a first part (e.g., connector or filter).

BRIEF DESCRIPTION OF THE DRAWING

FIG. 1 is a side elevational view of an embodiment of the inventive security device attached to a prior art cable filter

2

device (approximately 2:1 scale) in spaced relation to a signal source and output device shown in schematic;

FIG. 1A is a cross-sectional view of the cable filter and security device as taken generally along the line 1A-1A in FIG. 1;

FIG. 2 is an enlarged perspective view of the cable filter device housing and F-connector in spaced relation thereto;

FIG. 3 is the view of FIG. 2 with the F-connector attached to the cable filter device housing and the electric lead extending therefrom;

FIG. 4 is an enlarged perspective view of an embodiment of the security device first and second connector parts in spaced relation to each other;

FIG. 5 is the view of FIG. 4 showing the first and second connector parts in the assembled condition with the cylindrical sheath of the security device shown in spaced relation thereto;

FIG. 6 is the view of FIG. 3 showing the security device attached to the cable filter device and the security attachment/ removal tool shown in spaced relation thereto;

FIG. 7A is an end view of the sheath;

FIG. 7B is the view of FIG. 7A including the first and second connector parts located within the sheath;

FIG. 8 is a perspective view similar to FIG. 6 except showing the security device in spaced relation to the filter and further showing another embodiment of tool which may be used to attach the security device to the filter; and

FIG. 9 is a perspective view of another embodiment of the security device attached to the connector end of an R59 CATV cable.

DETAILED DESCRIPTION OF A PREFERRED EMBODIMENTS

Referring to the drawing, there is seen in the Figures a security device generally indicated by reference numeral 10 adapted for mounting between a first part and a second part to inhibit unauthorized removal or detachment of the first part from the second part. The first and second parts can be any types of parts where it is desired to prevent or inhibit the removal of the parts from each other. The first part may take the form of a device such as the cable filter device indicated generally by the reference numeral 12 in FIGS. 1-3 and 8, or an R59 CATV cable and connector as seen in FIG. 9.

Referring first to attachment of the security device to the cable filter example, cable filter device 12 is known (also referred to as a "trap") and operates to prevent transmission of unauthorized channels or other communication information from signal source 14 (e.g., cable junction box receiving transmission from cable company) and signal source connector 14a through to the cable 16 which connects to the signal output device 18 (e.g., television set). In particular, cable filter device 12 includes an electronic device such as a chip or a printed circuit board (PCB) 20 which may be programmed by the cable company to prevent transmission of unauthorized signals therethrough. Electric leads 22 and 24 extend from opposite ends of PCB 20 to carry the signals through the PCB from source 14 to device 18, respectively. Absent cable filter device 12, cable 16 would connect directly to source 14 via female F-connector 16a and male F-connector 14a.

As discussed previously, cable filter devices which do not have a security device allow the unscrupulous person to easily remove the filter and illegally receive unauthorized signals. Although such security devices have been proposed before, the present invention provides a security device which is very effective at inhibiting unauthorized removal of the cable filter device 12 (or other device or part which is only meant to be

removed from a second part by authorized personnel). As will be discussed in detail below, a special tool is required to remove filter device 12 from the part to which it is connected, thus inhibiting anyone not having the special tool from removing cable filter device 12.

A common type of coax cable connectors are known in the industry as "F-connectors". An F-connector 28 (FIGS. 1A, 2 and 3) having a male end 28a and opposite female end 28b having internal threads 28b' is provided with male end 28a fixed to a first end 26a of the cylindrical housing 26 of cable filter device 12. The opposite second end 26b of housing 26 is in the form of a male threaded shank for removable attachment to coax cable female F-connector 16a (FIG. 1). Housing 26 includes an axial bore 26' extending entirely therethrough from first end 26a to second end 26b thereof. As seen best in FIG. 2, F-connector 28 is rotationally fixed to housing 26 via longitudinally extending splines 28c which mate with cooperatively formed splines 26c located on the inner wall 26d of housing 26. Housing 26 and connector 28 are also axially secured together by a rolling operation performed on housing end 26a which deforms and presses ("crimps") the terminal edge thereof radially inward onto the annular shoulder 28d of connector 28. As seen in FIG. 3, in the fully attached condition, F-connector female end 28b protrudes from housing 26. A conductor extension 22a is collinearly attached to electric lead 22 and is of a length sufficient to extend through security device 10 and make connection with signal source 14 in the fully attached condition as will be described further below. An axial locator element 23 and plug 25 may be provided at housing end 26b through which opposite lead 24 extends to maintain axial positioning thereof with respect to housing 26.

Referring now to security device 10, as seen best in FIGS. 4 and 5, security device 10 includes a connector 30 and cylindrical sheath 32 which extends in covering relation to connector 30 in the fully assembled condition with filter device 12 as seen in FIGS. 1, 1A and 6. Connector 30 is itself comprised of first and second connector parts 34 and 36, respectively. First connector part 34 includes a first male end in the form of a threaded shank 34a and a second female end 34b having a head portion 34b' which is preferably non-circular to allow engagement with a tool and is preferably in the form of a hexagon. An axial bore 34c extends the entire length of first connector part 34. Second connector part 36 includes a first male end 36a in the form of a non-threaded, smooth surface shank 36a having a smaller diameter free end portion 36a' forming a shoulder 36a" with larger diameter portion 36a to assist in axially locating first and second connector parts 34 and 36 together in the manner described below. Second connector part 36 further includes a second female end 36b having a head portion 36b' which is preferably non-circular to allow engagement with a tool and is preferably in the form of a hexagon and includes internal threads 36b". An axial bore 36c extends the entire axial length of second connector part 36.

First and second connector parts 34 and 36 are secured together in coaxial alignment with shank 36a of second connector part 36 located within bore 34c of first connector part 34 and second component head portion 36b in abutting contact with first component head portion 34b. As seen in FIG. 1A, first component first end 34a includes a radially inwardly directed flange 34a" defining a narrowed opening through which smaller diameter shank end portion 36a' extends and against which shoulder 36a" abuts. An O-ring 38 is located at the interface of first component head portion 34b and second component head portion 36b. Since the interface between the

shanks and head portions of the first and second components is smooth, the components may rotate freely with respect to each other.

Sheath 32 includes a central bore 32' extending entirely therethrough from first end 32a to second end 32b. Connector 30 (comprising assembled connector components 34 and 36) is inserted into sheath bore 32' at second end 32b thereof as seen in FIG. 5. In the fully assembled condition of the security device 10, cylindrical sheath 32 lies in covering relation to connector 30 with second sheath end 32b lying substantially flush with second component head surface 36b". The diameter D₁ of sheath bore 32' is only slightly larger than the maximum diameter D₂ of first and second component head portions 34 and 36 such that these surfaces lie in closely adjacent yet freely rotatable relationship to each other as seen in FIGS. 1, 1A, 6 and 7. The "points" of the hexagonal head portion 36b define the maximum diameter D₂ with the intermediate flat surfaces thereof defining the minimum diameter D₃. With D₃ smaller than D₁, longitudinally extending gaps G₁-G₆ are formed between component head portions 34, 36 and sheath 32 in annularly spaced fashion about and between the head components 34b, 36b and the sheath inner bore surface 32" (FIG. 7). Gaps G₁-G₆ allow entry and exit of specially configured tools 50 seen in FIGS. 1, 1A and 6 and tool 52 seen in FIG. 8, both of which will be described more fully below.

As seen in FIGS. 1A and 7A, a radially inwardly extending annular flange 32c is located on sheath inner wall 32" approximately 1/3 down the length of sheath 32 from first end 32a to second end 32b and has an inner edge flange diameter D₄. Upon fully inserting connector 30 into sheath 32, first connector head portion 34b abuts flange 32c.

In one embodiment of security device 10, the maximum diameter D₆ of threaded shank 34a (FIG. 4) is slightly less than the inner edge diameter D₄ of flange 32c. As such, component 30 freely inserts into sheath 32 without any rotation of the component relative to the sheath 32 required. As such, in this embodiment, component 30 and sheath 32 are loosely held together until they are attached to cable security device 12 or other part.

In a second, more preferred embodiment of security device 10, inner flange edge 32c" is threaded and of a diameter such that as component 30 is passed into sheath bore 32', threaded shank 34a engages and must be rotated relative to sheath 32 to extend past flange 32c. In this embodiment, the threads adjacent head portion 34b' are relieved to provide a smooth surface relief area as indicated at 34a" in FIG. 5. Once flange 32c reaches and is located within relief area 34a", component 30 and sheath 32 may rotate freely with respect to each other without axial translation of one with respect to the other. When handling security device alone (without attachment to any other part as of yet), sheath 32 may be removed from component 30 only by holding component 30 fixed and rotating sheath 32 in the opposite direction which again engages threaded shank 34a through flange 32c to withdraw component 30 in the opposite direction to which it was inserted into sheath 32. This embodiment therefore allows preassembly of component 30 to sheath 32 allowing easy shipping and handling during installation onto cable security device 12 (or other part).

With component 30 and sheath 32 assembled together in the manner described above, security device 10 may now be attached between first and second parts having attachment components which will mate with the attachment portions of security device 10. More particularly, as seen in the embodiment of FIG. 1A, security device 10 is attached to cable security device 12 by threading shank 34a into

F-connector female end **28b**. As mentioned above, this assembly may be done either at the manufacturer or in the field. As seen in FIG. 8, a specially configured tool **52** may be used to tighten security device **10** to filter device **12**. In particular, tool **52** includes at least one but preferably two prongs **52a** and **52b** extending from a head portion **52c** and T-style handle **52d** used to manually grip tool **52**. Each prong **52a** and **52b** is of a length L_3 which is longer than the length L_2 of second component head portion **36b** (FIG. 4) so that when prongs **52a** and **52b** are inserted into any pair of diametrically opposed gaps G_1-G_4 , G_2-G_5 , or G_3 , G_6 located between components **34**, **36** and sheath **32** (FIG. 7B), the prongs reach first component head portion **34b**. As such, both component heads portions **34b** and **36b** are engaged and may be rotated together to thread and tighten threaded shank **34a** into female threaded end **28b** following which tool **52** may be withdrawn from the selected pair of diametrically opposed gaps G_1-G_6 .

Security device **10** together with cable filter device **12** is then attached to second part **14** (e.g., the communication data source) by threading female end **36b** onto male connector **14a**. A different specially configured tool **50** is provided which is required to alternately secure and remove security device **10** to and from another part at female end **36b**. More particularly, tool **50** includes a C-shaped segment **50a** from which extends a main arcuate wall segment **50a** with at least one but preferably two prongs **50c** and **50d** extending perpendicularly from C-shaped segment **50a**. As described above, first and second components **34**, **36** may rotate freely with respect to each in the assembled condition seen in FIG. 5. With sheath **32** covering components **34**, **36**, in order to secure connector female end **36b** onto male end **14a**, tool **50** is used by inserting prongs **50c**, **50d** into any pair of diametrically opposed gaps G_1-G_4 , G_2-G_5 , or G_3 , G_6 located between components **34**, **36** and sheath **32** (FIG. 7B). The length L_1 of tool segments **50c**, **50d** (FIG. 1A) is not longer than the length L_2 of second component head portion **36b** (see FIG. 4) such that prongs **50c**, **50d** extend to reach and engage only first component head portion **34b**. As such, prongs **50c**, **50d** may only rotate component **36** which will rotate independently with respect to component **34**. It is noted main arcuate wall segment **50a** is of a radius only slightly larger than the radius of sheath **32** such that main arcuate wall segment **50a** will engage the exterior surface of sheath **32** and thereby assist with stabilizing tool **50** on security device **10** and also assist with the proper alignment of tool prongs **50b** and **50c** as they are inserted into the selected pair of diametrically opposed gaps G_1-G_4 , G_2-G_5 , or G_3 , G_6 . In the engaged position, the user manually grasps and turns C-shaped segment **50a** which causes the rotation of second component **36** onto end **14a**. It will be appreciated that sufficient clearance must exist between sheath end **32b** and first part **14** structure (e.g. housing) or other structure surrounding the attachment point at end **14a** to allow tool **50** to be inserted between sheath end **32b** and the surrounding structure. The clearance provided should not be much larger than to allow the relatively short tool **50** to

engage security device **10** as described above. Limiting this clearance reduces the chance of an unauthorized person inserting another type of tool (e.g., a screwdriver) into gaps G_1-G_6 which is required to reach and rotate first component head **34** as discussed above.

Since sheath **32** covers and freely rotates about component parts **34** and **36** as described above, they are not accessible without specially configured tool **50**. There is thus no surface accessible to fix components **34** and **36** in place while attempting to rotate and remove cable filter device **12** therefrom. Thus, any rotation of housing **26** will simply result in the free rotation of first component part **34** while second component part **36** remains rotationally fixed. As such, no axial translation between or detachment of the parts will occur. Furthermore, any attempt to insert a tool into sheath end **32a** will be futile as it will not reach second component part **34** due to the presence of female end **28b** and flange **32c** (FIG. 1A).

With cable filter device **12** attached to security device **10** and first part **14**, cable output device **18** may be attached to end **26b** by threading female F-connector **16a** of cable **16** onto male F-connector end **26b** of cable filter device **12** (FIG. 1) to thereby establish the signal connection between source **14** and output device **18**.

FIG. 9 shows an embodiment of security device **10** which is secured directly to the connector **60** on an R59 cable having a connector **64** at the opposite end of the cable **62**.

As discussed above, security device **10** may be used to couple any two parts together which already have or are adapted to connect to connectors configured to mate with the opposite ends of the security device. It is therefore understood that the present invention is therefore not limited to the particular device attachment embodiments shown and described herein.

What is claimed is:

1. A security device for inhibiting unauthorized removal of a first part from a second part, said security device comprising:
  - a) a connector having first and second connector parts freely rotatably connected to each other, said first connector part having a threaded male end for removable attachment to a first part, said second connector part having a female threaded end located opposite said first connector part male end adapted for removable attachment to a second part; and
  - b) a cylindrical sheath having an inner wall defining a central bore, said inner wall including a flange positioned adjacent a smooth annular area located on said first connector part male end, said flange and said smooth annular area forming a freely rotatable connection between sheath and said connector, said sheath extending about said first and second connector parts in covering relation thereto.

* * * * *
